Planned Office
Attorney

Patented Dec. 8, 1925.

UNITED STATES PATENT OFFICE.

JOHN E. WALTER, OF BALTIMORE, MARYLAND.

ATTACHMENT FOR GAS RANGES.

Application filed February 6, 1925. Serial No. 7,301.

To all whom it may concern:

Be it known that I, JOHN E. WALTER, a citizen of the United States, residing at Baltimore, State of Maryland, have invented 5 certain new and useful Improvements in an Attachment for Gas Ranges, of which the following is a specification.

The present invention relates to an attachment for gas ranges and the like and 10 has for its principal object to provide means for preventing the turning on of the gas cocks leading from the supply to the burners.

Another important object of the invention 15 is to provide an attachment of this nature which may be easily attached to the supply pipes of the gas range and may be swing to an out-of-the-way position when desired.

Another important object of the invention 20 is to provide an attachment of this nature with means for holding it in an operative position in the path of the handles of the gas cocks so as to prevent turning thereof.

A still further object of the invention is 25 to provide an attachment of this nature possessed of an extremely simple and efficient structure, one which is effective and reliable, inexpensive to manufacture, capable of being used on practically all conventional forms of gas ranges, strong, durable, not liable to readily get out of order, and otherwise well adapted for the purpose for which it is designed.

With the above and numerous other objects in view as will appear as the description proceeds, the invention resides in certain novel features of construction, and in the combination and arrangement of parts as will be hereinafter more described and 40 claimed.

In the drawing—

Figure 1 is a fragmentary top plan view 45 of a gas range showing my attachment associated therewith,

Fig. 2 is a fragmentary front elevation thereof,

Fig. 3 is an enlarged detail vertical section taken substantially on the line 3—3 of Fig. 1, and

Fig. 4 is a detail view of the attachment 50 showing the means for holding the same in an operative position.

Referring to the drawing in detail, it will be seen that F designates generally a gas 55 range which is provided with the usual supply pipe P having the branches B extend-

ing inwardly toward the range for supplying the various burners (not shown) and having incorporated therein the conventional form of cocks C operable by the handles H. My attachment consists of an elongated parallel piped bar 5 carried by spring clips 6 which are substantially U-shaped in formation and include curved jaws 7 adapted to straddle the supply pipes 65 P as is shown to advantage in Fig. 3.

The bar 5 may be swung so as to be positioned in the full line position shown in Fig. 3 or in the dotted line position shown in the same figure. When in the full line position, said bar is located in the path of movement of the handles 8 and prevents the opening of the valve controlled by said handle. When in this dotted line position, it will be 70 seen that the handles are free to swing outwardly from the range for opening the gas cocks C.

A sleeve 9 is slidably mounted on the bar 5 and pivotally supports a catch member 10 by means of a pin or the like 11. The upper 80 end of this catch is offset as at 12 to allow ready operation thereof while the lower end thereof is curved to form a hook 13 for engaging one of the branches B as is clearly shown in Figs. 3 and 4 so as to hold the bar 85 in its upright or operative position as shown in full lines in Fig. 3.

It is thought that the construction and operation of the attachment will be clearly understood without a more detailed description thereof. It will be apparent from the above that this attachment is possessed of an extremely simple structure which is both efficient and effective and which will be thoroughly reliable in operation. The present 90 embodiment of the invention which I have given by way of example possesses all the features of advantage enumerated as desirable in the statement of the invention and the above description and it is desired to point out that different changes in the details of construction, in the materials, in the dimensions, and in the combination and arrangement of parts may be resorted to without departing from the spirit or scope of the 95 invention as hereinafter claimed or sacrificing any of its advantages.

Having thus described my invention, what I claim as new is:

1. An attachment of the class described 100 including an elongated bar, spring clips on the bar for attaching the same to the supply

pipe of a gas range, a sleeve slidable on the bar, and a hook on the sleeve for engaging a branch extending from the supply pipe so as to hold the bar in an operative position.

5 2. An attachment of the class described including an elongated bar, a pair of clips of U-shaped formation having their intermediate portions fixed to an edge of the bar and having their sides curved for revolv-

ably engaging a supply pipe on a gas range, 10 a sleeve slidably mounted on the bar between the clips, and a catch pivoted intermediate its ends to the sleeve, one end of the catch being offset to provide an operating handle and the other end being curved to form an 15 engaging hook.

In testimony whereof I affix my signature.
JOHN E. WALTER.
